UNITED STATES PATENT OFFICE

2,537,547

GEAR MOTOR OPERATOR FOR BOOSTERS

Paul C. Pocock, Marion, Ohio, and Howard M. Purcell, Philadelphia, Pa., assignors to H-P-M Development Corporation, Wilmington, Del., a corporation of Delaware

Application August 1, 1947, Serial No. 765,280

8 Claims. (Cl. 103—11)

1

This invention relates to hydraulic circuits, and particularly to hydraulic circuits employing fluid intensifiers of the type disclosed in the Warren R. Tucker application, Serial #594,413, filed May 18, 1945, now Patent No. 2,486,079, and assigned to the same assignee as the present application.

The fluid pressure intensifier disclosed in the Tucker application is characterized by including a valve member which must be driven in order to make the said intensifier effective. When the valve member is not driven the intensifier is, in effect, a closed valve.

This characteristic of the fluid pressure intensifier with which the Tucker application is concerned, is utilized to advantage by making the said converter selectively effective or ineffective merely by controlling the driving of the valve member. This substantially simplifies the valving problem in any hydraulic circuit in which the intensifier is employed and especially in view of the fact that pressures upward of five and six thousand pounds per square inch are delivered by the pressure intensifier.

The primary object of the present invention is to provide an improved arrangement for selectively starting and stopping the valve member of a hydraulic intensifier thereby to control its period of effectiveness.

Another object of this invention is to provide fluid operable means responsive to pressures in the circuit being supplied for controlling the effectiveness of a fluid pressure intensifier.

It is also an object of this invention to provide a control means for a fluid pressure intensifier in a hydraulic circuit such that electric switches and auxiliary electric motors and the like are entirely eliminated.

It is a still further object of this invention to provide a means for selectively driving the valve member of a hydraulic intensifier and to provide in combination therewith means for selectively controlling the speed of the valve member.

These and other objects and advantages will become more apparent upon reference to the following description taken in connection with the accompanying drawings in which:

Figure 1 is a diagrammatic view of a press circuit having a pressure intensifier with a control means according to this invention;

Figure 2 is a fragmentary circuit showing a different manner of connecting the control circuit; and

Figure 3 is a sectional view showing a flow controlling valve to be employed in the control circuits of Figures 1 and 2.

General arrangement

According to this invention there is provided a source of pressure fluid such as a pump for sup-

plying actuating fluid to a hydraulic motor such as a press ram. Connected between the pump and the ram is a fluid pressure intensifier adapted for receiving the discharge of the pump and for converting it to a higher pressure and discharging it to the said ram. This intensifier includes a valve member which must be driven during the period that the intensifier is effective. According to this invention there is provided a fluid operable motor such as a gear motor, for driving the intensifier valve member.

In order to make the intensifier effective during any predetermined period, means are provided for only supplying actuating fluid to the said gear motor during that period. This is preferably accomplished by a normally closed valve positioned between the gear motor and the pressure side of the hydraulic circuit and adapted for being operated into open position in response to a predetermined pressure in the said circuit. According to one modification of this invention the supply pump is reversible in delivery and one port of the gear motor is connected with one side of the pump and the other port thereof is connected with the other side. The gear motor thus runs in opposite directions depending on which way the pump is delivering to the supplied circuit. According to another modification the gear motor has one port connected with exhaust and its other port connected through normally closed valves with both sides of the pump. The valves selectively open to connect the gear motor with the pressure side of the pump when it is desired to make the pressure intensifier effective.

The supply circuit for the gear motor preferably includes speed controlling means, such as a flow controlling valve, whereby the speed of rotation of the intensifier valve member is only that necessary to accommodate the quantity of fluid being passed therethrough.

Structural arrangement

Referring to the drawing more in detail, there is shown in Figure 1 a double acting press ram 10 which is reciprocably mounted in a cylinder 12. A pump 14 of reversible delivery has one port connected through a conduit 16 with the upper end of cylinder 12 and in the said conduit is a check valve 18 opening away from the pump. The other side of the pump has connected therewith a conduit 20 which leads to one port of a valve 22 which also has a port 24 connected with the lower end of the cylinder 12, and a port 26 connected with the port 28 of a similar valve 30. The valve 22 has therein a valve member 32 which is normally urged by a spring 34 into position to connect the port 24 with the conduit 20 and to disconnect the port 24 from the port 26. The valve 30 is similar to the valve 22 and includes a port 36 which is connected with the

60

discharge port of the fluid pressure intensifier 38, and a port 40 which is connected with the conduit 16 between the check valve 18 and the upper end of the cylinder 12. The valve 30 also has a valve member 42 which is normally urged by a spring 44 into position to connect the ports 28 and 36 and disconnect the ports 36 and 40.

The fluid pressure intensifier 38 has an inlet port which is connected by a conduit 46 with the port 48 of a valve 50. The valve 50 also has a port 52 connected with the conduit 16 and a port 54 connected with the conduit 20. A valve member 56 in the valve 50 is movable by pressure in either of the ports 52, 54 into position to connect the said port with the port 48.

As mentioned before the fluid pressure intensifier 38 has a valve member which must be driven in order to make the said intensifier effective. This valve member has a shaft 58 to which is connected the gear motor 60. The gear motor 60 has one port connected by a conduit 62 through a check valve 64 with the conduit 16, the said check valve opening toward the conduit 16. The other port of the gear motor 60 is similarly connected through a conduit 66 and a check valve 68 with the conduit 20.

Bypassing the check valve 64 is a normally closed valve 70 having therein the valve member 72 which is movable by fluid pressure conducted thereto from the discharge side of the check valve 18 by the conduit 74 to place the valve 70 in its open position. In series with the valve 70 is a flow controlling valve 76 which is operable, as will be explained hereinafter to control the rate of fluid flow therethrough.

The check valve 68 is similarly bypassed by the normally closed pressure responsive valve 78 and the flow controlling valve 80 in series therewith. The pressure responsive valve 78 is connected to be moved to its open position by pressure in the lower end of the cylinder 12 by the conduit 82.

The construction of the flow controlling valves 76 and 80 is best seen in Figure 3. Each of these valves comprise a valve member 84 which has the side port 86 in communication with the inlet port of the valve and a passage 88 communicating with the outlet port. In the discharge conduit of the valve there is an adjustable choke valve 90 and connected to the outlet of the valve 90 is a conduit 92 which leads to the spring chamber 94. The spring 96 urges the valve member 84 leftwardly into a position of minimum restriction of fluid flow through the valve. Movement of the valve member toward the right will set up a restriction to fluid flow therethrough. It will be apparent that the valve member is urged rightwardly by the pressure standing in the channel 88 and leftwardly by the combined action of the spring 96 and the pressure in the chamber 94. In accordance with the setting of the valve 90 the flow control valve will thus permit fluid flow therethrough at a predetermined rate which will create a pressure drop across the valve 90 equal to the thrust of the spring 96.

In Figure 2 there is shown an arrangement similar to that shown in Figure 1 and which is similarly numbered with the addition of a subscript *a* except that the gear motor 60a has one port thereof continuously connected with exhaust by a conduit 98, while the other port of the said motor is connected through a flow controlling valve 100 with both of the discharge sides of the normally closed pressure responsive valves 70a and 78a.

By the arrangement shown in Figure 2 the gear motor 60a is caused always to rotate in the same direction and one of the flow controlling valves shown in Figure 1 can be eliminated. The circuits of Figures 1 and 2 are otherwise identical in every respect.

Operation

In operation, the press ram 10 is caused to advance downwardly by bringing about the delivery of the pump 14 to the conduit 16. After the press ram has engaged the work and a predetermined pressure is built up thereon the valve 70 is shifted open by pressure conducted thereto through the conduit 74. The supply of pressure fluid now flows from the conduit 16 through the valve 70, the valve 76 and the conduit 62 to the gear motor 60. This drives the gear motor in rotation and fluid is exhausted from the other port thereof through the conduit 66, valve 68 and conduit 20 to the suction side of the pump 14.

The valve member 56 of the valve 50 was previously shifted downwardly by the pressure in conduit 16 so that the inlet of the intensifier 38 is connected to receive fluid from the conduit 16. Similarly, the pressure in the conduit 16 had previously moved the valve member 42 of the valve 30 downwardly so that the discharge from the pressure intensifier is connected directly with the upper end of the cylinder 12. Under these conditions the intensifier delivers high pressure fluid to the upper end of the cylinder 12 and the ram advances further into the work.

It will be noted that the check valve 18 prevents the high pressure fluid from being conveyed back to the discharge side of the pump 14, and that the valve 70 remains open because its pilot conduit 74 is connected to the high pressure side of check valve 18.

Upon completing the work to be done by the ram 12, the pump 14 is reversed so that it delivers into the conduit 20. The fluid flows through conduit 20 and valve 22 to the lower end of the cylinder 12 and moves the ram 10 upwardly. At this time the surge valve 102 opens by pressure conducted thereto by the conduit 104 and exhausts the upper end of the cylinder 12 to the reservoir 106.

The valve member 56 of the valve 50 will return to its Figure 1 position and the valve member 42 of the valve 30 will also return to its Figure 1 position.

Should the ram 10 encounter resistance during its retracting movement the valve 78 will be piloted open by fluid conducted thereto by conduit 82 and bring about a supply of actuating fluid to the gear motor 60. This will again make the fluid pressure intensifier 38 effective and fluid will be delivered therefrom through the valve 30 to the port 26 of valve 22. This will move the valve member 32 downwardly to interconnect ports 26 and 24 to direct the discharge from the intensifier to the lower end of the cylinder 10. Should the resistance to upward movement of the ram 10 diminish, then the valve 78 will again close making the intensifier 38 ineffective thus permitting movement upwardly of the valve member 32 and again interconnecting the conduit 20 with the port 24.

In the operation of the embodiment of Figure 2 similar conditions obtain except which ever of the valves 70a or 78a are opened, the fluid flow therefrom will always pass through the flow controlling valve 100 and drive the motor 60a in the same direction.

It will be apparent that the circuit of this invention provides a means whereby the fluid pressure intensifier is made selectively effective or ineffective and in response to pressure conditions in the supplied circuit. Furthermore, the operation of the intensifier is brought about by a fluid motor which derives its motive power from pressure fluid taken from the supplied circuit.

It will be understood that this invention is susceptible to modification in order to adopt it to different usages and conditions and, accordingly, it is desired to comprehend such modifications within this invention as may fall within the scope of the appended claims.

We claim:

1. In a hydraulic circuit; a pump; a fluid pressure intensifier connected to receive the discharge of said pump and having a rotary valve member which must be driven in order to make the intensifier effective; a fluid motor drivingly connected with the valve member of said intensifier; a normally closed valve connecting said motor with said pump; and means responsive to a predetermined discharge pressure of said pump for opening said valve thereby to drive said motor and to make said intensifier effective.

2. In a hydraulic circuit; a pump; a fluid pressure intensifier connected to receive the discharge of said pump and to increase the pressure thereof; a valve member in said intensifier which must be driven in order to make the said intensifier effective; a fluid operable motor connected to drive said member; means responsive to a predetermined discharge pressure of said pump to bring about a supply of actuating fluid to said motor; and means connected with said motor for controlling the speed of operation thereof.

3. In a hydraulic circuit; a pump; a fluid pressure intensifier connected to receive the discharge of said pump and to increase the pressure thereof; a valve member in said intensifier which must be driven in order to make the said intensifier effective; a fluid operable motor connected to drive said member; means responsive to a predetermined discharge pressure of said pump to bring about a supply of actuating fluid to said motor; and means connected with said motor for controlling the speed of operation thereof, said last mentioned means including flow controlling means connected in circuit with said motor and operable to determine the rate of fluid flow therethrough.

4. In combination; a reversible delivery source of pressure fluid; an intensifier having an inlet and an outlet; automatically operable means for connecting said inlet with the discharge side of said source; said intensifier including a valve member which must be driven to make said intensifier effective; a fluid motor drivingly connected with said valve member and connected in parallel with said source; normally closed valves connected between each side of said source to said motor; and means responsive to a predetermined pressure at either side of said source for actuating the valve connected between that side and said motor into open position.

5. In combination; a reversible delivery pump; an intensifier having a low pressure inlet and a high pressure outlet; valve means responsive to pressure at either side of said pump for connecting that side with said inlet; a valve member for said intensifier which must be driven to

make said intensifier effective; a fluid motor drivingly connected with said member and being hydraulically connected in parallel with said pump; means permitting free flow of fluid from either side of said motor toward said pump but preventing flow in the opposite direction; normally closed valves bypassing said last mentioned means; and pressure responsive means associated with each of said normally closed valves and hydraulically connected with the same side of the pump and operable in response to a predetermined pressure therein to move the said valve into its open position.

6. In combination; a reversible delivery pump; an intensifier having an inlet and an outlet; valve means operable automatically to connect the discharge side of said pump with said inlet; a valve member in said intensifier which must be driven to make said intensifier effective; a fluid motor connected to drive said member and being connected in parallel with said pump; a check valve in each of the connections between said pump and motor and opening toward the former; normally closed valve means bypassing each of said check valves; pressure responsive means for each of said normally closed valves responsive to a predetermined pressure at the pump side thereof for moving the associated valve into open position; and speed controlling means for said motor operable to control the speed thereof during the supply of fluid thereto from either side of said pump.

7. In combination; a reversible delivery pump; a fluid motor; check valves connecting said motor and pump in parallel and opening toward the said pump; normally closed valves bypassing said check valves and operable automatically in response to a predetermined pressure at the pump side thereof for opening to permit fluid flow to said motor; and speed control means operable to predetermine the rate of speed at which the said motor operates.

8. In a hydraulic circuit; a fluid displacement pump; a fluid pressure intensifier having an inlet connected to receive fluid from said pump, an outlet, and a rotary valve member, said intensifier being operable upon rotation of the valve member to receive fluid under a given pressure at the inlet thereof and redischARGE at least a portion of such fluid from the outlet at increased pressures; a fluid-actuated motor connected to rotate the valve member of said intensifier; and means connected between said fluid motor and said pump and responsive to a predetermined discharge pressure of said pump for supplying actuating fluid to said motor.
